ATTORNEY

UNITED STATES PATENT OFFICE.

JOHN D. HAMAN, OF WILMINGTON, DELAWARE.

PIPE-WRENCH.

1,308,353.

Specification of Letters Patent.

Patented July 1, 1919.

Application filed September 25, 1918. Serial No. 255,658.

To all whom it may concern:

Be it known that I, JOHN D. HAMAN, a citizen of the United States, residing at Wilmington, in the county of New Castle and State of Delaware, have invented certain new and useful Improvements in Pipe-Wrenches, of which the following is a specification.

This invention relates to tools of the wrench type, and more particularly to wrenches designed for operating in connection with pipe and like work.

The principal object of the invention is the provision of novel operating means whereby the movable jaw may be easily and conveniently adjusted to the work.

A further purpose of the invention is the provision of means whereby the adjusting nut may be rotated from the grip or handle 20 end of the wrench and by the same hand employed for grasping and manipulating the wrench, thereby leaving the other hand free for holding the work or for any other desired purpose.

25 The invention also has for its object to provide a wrench involving a simple and durable structure and which while admitting of adjustment by the same hand operating the wrench, also allows for the ratcheting 30 movement peculiar to pipe wrenches.

The drawing illustrates a preferred embodiment of the invention, however, it is to be understood that in adapting the same to meet different conditions, various changes in 35 the form, proportion, and minor details of construction may be resorted to without departing from the nature of the invention as claimed hereinafter.

In the drawings:—

40 Figure 1 is a view in elevation of a pipe wrench embodying the invention.

Fig. 2 is a transverse section on the line 2—2 of Fig. 1 looking to the right as indicated by the arrows.

45 Fig. 3 is a transverse section on the line 3—3 of Fig. 1 looking to the left as indicated by the arrows.

Corresponding and like parts are referred to in the following description and indicated 50 in all the views of the drawings by like reference characters.

The wrench comprises a handle member or shank 1 which is widened at one end and toothed to provide the fixed jaw 2. The opposite end of the shank or handle member is reduced and receives a grip or handle 3.

A head frame 4 is mounted upon the member 1 and is pivoted thereto by a suitable fastening 5. The frame 4 has a transverse slot 6 to receive a gear nut 7. A longitudinal opening is formed in the head frame 4 and receives the shank 8 which is provided at its outer end with a jaw 9. The element 9 constitutes the movable or adjustable jaw and its shank 8 is flat and its opposite edges 65 are formed with toothed segments which mesh with the thread of the gear nut 7. The frame 4 is also provided with a second longitudinal opening through which the shank or handle member 1 passes. A flat spring 10 is 70 secured at one end to the member 1 and has its opposite end entering the opening of the frame 4 and exerting an outward pressure thereon to hold the movable parts in predetermined position.

75 A shaft 11 is disposed parallel with the member 1 and is mounted at one end in the head frame 4 and at its opposite end in a tail frame 12 which is received upon the reduced end of the member 1. A pinion 13 is secured to the shaft 11 and in mesh with a gear wheel 14 mounted upon the reduced end of the member 1 and confined thereon by the grip 3 and tail frame 12. The gear wheel 14 constitutes an operating member whereby 85 the shaft 11 may be rotated by the same hand grasping and manipulating the wrench.

The forward end of the shaft 11 is provided with a pinion 15 which is in mesh 90 with the outer toothed portion of the gear nut 7. The ends of the pinion 15 are made rounding so as to allow for the pivotal movements of the head frame 4. The shaft 11 is enlarged a short distance from the 95 pinion 15 as indicated at 16 to form an annular shoulder and the pinion in the head frame 4 through which the forward end of the shaft 11 passes is enlarged to receive the enlarged portion 16 of the shaft as shown 100 most clearly in Fig. 1.

When adjusting the wrench embodying the invention, the hand grasping the grip or handle 13 may be utilized for rotating the gear wheel 14 and the movement of such gear 105 wheel is transmitted to the shaft 11 and to the gear nut 7, whereby the movable jaw 9 is adjusted away from or toward the fixed jaw 2 when adapting the wrench for operation upon the work in hand. It will thus be 110 understood that the tool is of such a nature as to admit of one hand of the workman

being free for any desired purpose while the remaining hand is used both for operating the wrench and for adjusting the same to the work. It is to be understood that sufficient play is provided with between the shaft 11 and its bearings to allow for pivotal movement of the head frame 4 so that the wrench may ratchet in a manner well understood.

- 10 The foregoing description and the drawings may be referred to as what may be considered the preferred, or approved form of my invention. It is to be understood that I may make such changes in the construction, 15 arrangement, and combination of parts, materials, dimensions, et cetera, as may prove expedient and fall within the scope of the appended claims.

Having thus fully described my invention, 20 what I claim as new and desire to secure by Letters Patent, is:—

- 25 1. A wrench, comprising a shank having a fixed jaw, a frame pivoted on the shank, a movable jaw having a threaded shank slideable in the said frame, a gear nut mounted in the frame and receiving the said threaded shank, a shaft mounted on the shank of the fixed jaw, a pinion at the front end of the shaft rotatable therewith and in mesh with 30 the gear nut, and operating means at the rear end of the shaft and including an element adjacent the grip or handle end of the wrench for imparting rotary movement to the shaft.

- 35 2. A wrench, comprising a shank having a fixed jaw, a frame pivoted on the shank, a movable jaw having a threaded shank slideable in the said frame, a gear nut mounted in the frame and receiving the said threaded shank, a shaft mounted at its forward end 40 in the pivoted frame and at its rear end on the shank of the fixed jaw, a pinion at the

forward end of the shaft in mesh with the gear nut, and operating means at the rear end of the shaft and including an element adjacent the grip or handle end of the wrench 45 for imparting rotary movement to the shaft.

3. A wrench comprising a shank having a fixed jaw, a head frame mounted upon the shank and pivoted thereto, a movable jaw having a shank adjustable in the head frame 50 and provided with thread sections, a gear nut mounted in the head frame and engaging the thread sections of the shank of the movable jaw, a shaft mounted at one end in the head frame and in mesh with the gear nut, and gearing connecting the rear end of the shaft with the shank of the fixed jaw and including a manually operable element adjacent the grip or handle end of the shank.

4. A wrench comprising a shank having a 60 fixed jaw, a head frame mounted upon the shank and pivoted thereto, a movable jaw having a shank slideable in the head frame and provided with thread sections, a gear nut mounted in the head frame and 65 coöperating with the thread sections of the shank of the adjustable jaw, a tail frame mounted upon the handle end of the main shank, a shaft mounted in the head and tail frame, a pinion at the forward end of the 70 shaft in mesh with the gear nut, a pinion on the rear end of the shaft, and a gear wheel mounted on the main shaft adjacent the grip or handle end thereof and in meshing relation with the teeth of the pinion at the rear 75 end of the shaft.

In testimony whereof I affix my signature in presence of two witnesses.

JOHN D. HAMAN.
